UNITED STATES PATENT OFFICE.

ALVA E. RAVENSCROFT, OF LOS ANGELES, CALIFORNIA, ASSIGNOR TO C. R. KIERULFF & CO., OF LOS ANGELES, CALIFORNIA, A COPARTNERSHIP CONSISTING OF C. R. KIERULFF AND ALVA E. RAVENSCROFT.

DOUBLE-DECK COMBINED TAKE-UP AND PAY-OUT WIRE REEL.

Application filed June 23, 1923. Serial No. 648,294.

To all whom it may concern:

Be it known that I, ALVA E. RAVENSCROFT, a citizen of the United States, residing at Los Angeles, in the county of Los Angeles and State of California, have invented a new and useful Double-Deck Combined Take-Up and Pay-Out Wire Reel, of which the following is a specification.

An object of this invention is to provide means whereby the work of linemen in erecting electric light, telegraph and telephone lines can be greatly facilitated and the labor reduced.

The invention is also applicable for repair work on such lines and for placing and for removing barbed wire for fences and the like.

An object of the invention is to provide means adapted to be mounted on and to be carried by a wagon or a truck and whereby wire may be simultaneously or successively paid out and taken up.

In this invention I have provided a single portable frame with reels, one above another to be revolved on such frame; and which frame and reels can be easily mounted on, fixed to and removed from the vehicle adapted to transportation.

Strength and simplicity of construction are further objects.

An object is to permit the use of two kinds of wire at the same time and to enable the paying out and taking up of each of the wires by only one man.

The invention includes the novel construction of frame and the various parts and combinations of parts whereby a plurality of coils of wires can be loaded on, carried, paid out and taken up, in or from any direction.

Another object is wide range for leading wire from the lower reel.

Other objects, advantages and features of invention may appear from the accompanying drawings, the subjoined detail description and the appended claims.

The accompanying drawings illustrate the invention.

Figure 1 is a perspective view of the invention shown in a service wagon with a coil of telephone wire on the upper reel and a coil of steel wire on the lower reel. The vehicle is shown fragmentally.

Fig. 2 is a plan view of the invention re-

moved from the vehicle and free from wire: 55 a portion of the upper deck is broken to expose the lower deck.

Fig. 3 is a fragmental detail showing the brake and casting for supporting same.

Fig. 4 is a detail showing the wire guide 60 and lock and method of locking the reel.

Fig. 5 is an elevation of the invention.

Fig. 6 is a section on line x^6 , Fig. 2.

Fig. 7 is a fragmental plan of the center of the frame. 65

Fig. 8 is a sectional elevation on line x^8 , Fig. 7.

Fig. 9 is a fragmental detail of the inner bottom or base ends of the frame members fastened to the base center piece. 70

The appliance is adapted to be variously positioned and for convenience will now be described as in the position shown in the drawings. There are two reels; viz, a bottom reel R and a top reel T mounted on a 75 frame or carrier.

The frame or carrier 1 comprises two members 2 and 3, one twice as long as the other and both formed of channel iron bent webwise, that is to say, with its web inside 80 the bend, into suitable form and fastened together at their ends. The member 2 is formed as a loop and has on each side of its center, three bends a , b and c , thus forming a central horizontal crown limb d , two 85 oblique side limbs e , two side uprights f and two bottom limbs g having base terminals h near the axis of the carrier. The member 3 practically corresponds to one-half of the member 2 having corresponding bends 90 and limbs, and is arranged at right angles to the member 2. The inner base ends h , h' of the three members are fastened to a base center piece 4 by suitable means as rivets 5. Said center piece is vertically beneath the top center or crown piece 6 which is fixed to the crown limb d by suitable means as rivets 7 passed through the web 95 of the channel iron.

The lower bends c are adapted to form supporting feet from which the limbs g converge upwardly toward a center so that when the feet rest on a suitable support as the platform or floor A of the vehicle B, the other parts will be free from the floor, and the feet can be fastened to the floor by the bolts C. 100

The bottom center piece 4 is shown cen-

trally raised or arched and the crown of the arch has a central threaded hole *j* which is alined with a threaded hole *k* in the upper end *d'*; the limb *d*, and the center crown piece 6.

8 and 8^a are axially alined axles for the upper and lower reels. The center pieces 4 and 6 may be of iron or any other suitable material cast or otherwise formed and the 10 axles 8 and 8^a are screwed into the holes *k* and *j* respectively, and are provided at their tops with transverse holes 9 for cotter pins 9'.

A bracket bearing 10 rests upon the upper 15 center piece 6 to support the thimble 11 which fits the axle 8 and is provided with a hub 12 at its bottom to rest upon the bearing 10. A corresponding thimble 11^a provided with a hub 12^a rests upon the lower 20 center piece 4. Said thimbles are provided respectively with broad flanges 13 and 13^a, and upon these flanges the reel disks 14 and 14' are fixed respectively by rivets 15.

The top 16 of the thimble 11 is squared to 25 receive a crank handle 17 and has a shoulder 18 that keeps the handle from slipping down, and the handle is fixed thereon by the cotter pin 9' and a washer 19.

The reel disk 14 is a plate or sheet of 30 metal and is downwardly rounded and flanged at its periphery as at 20 for rigidity.

In the disk 14 there are radial slots 21 equally spaced apart as best shown in Fig. 2 of the drawing, and in said slots there are 35 adjustably mounted prongs 22 around which the wire is wound as shown in Fig. 1.

The prongs 22 are adjustably held in place by winged nuts 23 for adjustment of the prongs and to clamp the prongs in place.

40 Each reel disk is provided with holes 24 similarly disposed and equally spaced to receive detents 32 forming parts of the combined wire guides and locks 25 which respectively comprise a clamp 26 that 45 is adjustably mounted on an oscillating upright guide rod 27 that is adapted to swing horizontally outside the reel disks and the frame, and that is supported by an arm 28 which extends between the 50 upper reel disk 14 and the frame 1, and is supported by a bracket 29 through which it may slide and with relation to which it is fixed by a set screw 30. Said bracket rests on and is supported by the crown or top 55 piece 6.

The guide rod 27 supports a wire guiding eyelet 31 that is between the clamp 26 and the detent 32. Said detent is adapted to fit into the holes 24 in the disk for locking the reel and eyelet in fixed relation to each other, as shown in Fig. 4 of the drawings.

60 The top brake comprises a hooked rod 33 horizontally arranged and having one end 34 formed in a semi-circular hook around 65 the thimble 11 between the flanges 12 and

13; and the other end has a winged nut 35 to engage an abutment 36 which extends up from the bracket 29, and through which the brake rod 33 extends. By turning the wing nut 35, the brake may be adjusted to afford 70 the desired friction of the hook upon the thimble, thus to prevent the reel from racing.

The bracket 29 rests on the top of the frame 1 and forms a bearing for the hub 12 75 of the thimble 11. A set screw 37 holds it firm and allows the guide rod 27 to be moved to any desired angle.

The bracket 29 is only used for the top 80 reel. The lower reel has a brake in the form of a rod 38 inclined at an angle with one end 39 forming a semi-circle around the casting 11^a between the flanges 12^a and 13^a and at the other end is provided with a wing nut 40 engaging a bracket 41 that supports 85 the rod at its outer end, and is bolted down to the platform floor A of the wagon or truck; and the brake for the lower reel can be adjusted by turning the winged nut 40.

As shown in the drawings the prongs on 90 the lower reel disk are shorter than the prongs on the top reel disk to allow enough room to clear the frame when the reel is in use. No handle is shown on the lower reel as the workmen prefer to turn the same 95 by directly grasping the disk or the prongs to turn it.

By making the frame of the loop 2 and brace 3 as shown, wide range of direction is allowed the wire on the lower reel and such wire may be led away through a range of nearly 180° without interference of the frame, the top reel has the full range of 360°, although such range is seldom required and can be secured by simply turning 105 the vehicle as desired.

The prongs 22 are of the usual curved form and may be swung round in their slots so as to allow a coil of wire to be put over the prongs to encircle the same and to rest 110 on the disks and to be held in position while the wire is paid out from or wound on to the coil; the paying out being effected by running the wire through the eye and drawing it out in the required direction; 115 and the winding up being effected by turning the disk by crank or otherwise.

I claim:

1. A wire reel comprising a frame composed of two pieces of channel iron; one of said pieces being a loop formed with a horizontal top limb and two bottom limbs, and side limbs connecting said top and bottom limbs, and means to hold said loop upright.

2. A wire reel comprising a frame composed of two pieces of channel iron; one of said pieces being a loop formed with a horizontal top limb and two bottom limbs, and side limbs connecting said top and bottom 130

- limbs; and a brace comprising a top limb, a bottom limb and a side limb, the ends of which are fastened to the top limb and to the bottom ends of the loop.
- 5 3. In a double disk wire reel, the frame set forth comprising two pieces of angle iron bent web-wise, one of which pieces is twice as long as the other and is bent into the form of a loop having a central horizontal limb at the top and converging limbs at the bottom terminating below said horizontal limb; a center piece fixed to the ends of the longer piece; a center piece fixed in the channel of the horizontal limb; and the 10 shorter piece having its ends fixed to the center pieces.
- 15

4. A double deck wire reel comprising a frame formed of channel iron and having a horizontal top limb; a center crown piece secured to said horizontal top limb; a bottom center piece secured to said frame in axial alignment with said center crown piece; axles secured to said center crown piece and said bottom center piece; thimbles rotatably mounted on said axles; and reels 20 25 secured to and supported by said thimbles.

In testimony whereof, I have hereunto set my hand at Los Angeles, California, this 16th day of June, 1923.

ALVA E. RAVENSCROFT. 30
